UNITED STATES PATENT OFFICE.

HIRAM W. RU TON, OF GOSHEN, INDIANA.

CARPET-SWEEPER.

No. 843,770.

Specification of Letters Patent.

Patented Feb. 12, 1907.

Application filed July 11, 1906. Serial No. 325,683.

To all whom it may concern:

Be it known that I, HIRAM W. RU TON, a citizen of the United States, residing at Goshen, in the county of Elkhart and State 5 of Indiana, have invented a new and useful Carpet-Sweeper, of which the following is a specification.

It is a well known fact that when floor or carpet sweepers of the ordinary type are operated the same are liable to tilt or turn upon the bail-pivots when the sweeper is drawn toward the operator.

One of the principal objects is to provide novel and very simple means for connecting the handle member or bail to the sweeper-case, said means effectively preventing the undesirable tilting action and being furthermore readily applicable to the sweeper-case without the necessity of cutting or otherwise 20 carefully fitting the parts in place.

The preferred form of construction is illustrated in the accompanying drawings; but an inspection of the claims will show that the invention is not limited to this particular 25 embodiment.

In the drawings, Figure 1 is a side elevation of the sweeper. Fig. 2 is a view, on an enlarged scale, of the means for securing the handle member thereto. Fig. 3 is a detail 30 sectional view on the line 3-3 of Fig. 2. Fig. 4 is a top plan view of the structure shown in Fig. 2. Fig. 5 is a detail sectional view showing a slightly-modified form of construction.

Similar reference-numerals designate corresponding parts in all the figures of the drawings.

The sweeper-body may be of any desired or well-known construction and includes a 40 case 6, having end walls, one of which is shown at 7. The handle member in the present form includes a shank or stock 3, the lower end of which fits into a socket-piece 9, forming a part of a bail. This bail includes 45 side arms 10. So far as thus described no particular claim is made to the parts, the invention residing in the means for connecting the handle member to the case, so that the desired pivotal connection of said member is 50 secured and the tilting action of the case prevented.

To secure the above results, a plate 11 is employed, having a flat rear side which abuts against the adjacent end wall of the case, 55 said plate having openings 12 to receive fasteners 13, passed therethrough into the end

wall. The plate, furthermore, has an opening 14 in the center of its lower portion, and a marginal rib 15 extends from the lower edge around the upper portion of the same, 60 said rib having a curved portion disposed concentric to the opening 14 and having a notch 16 disposed directly above the opening. In the present embodiment this rib increases in thickness toward the notch, as 65 clearly shown in Fig. 4; but this is not an essential feature. The bail-arm 10 terminates in an offset head 17, the inner face of which overlies the plate 11. This head is provided with an opening 18, alined with the opening 70 14 of the plate. A headed pivot-bolt 19 passes through the opening 18, the portion passing therethrough being of less diameter than the opening, as clearly shown in Fig. 3. Said bolt is provided with a shoulder 20, that 75 rests against the plate 11, the shank 21 of the bolt extending through the opening 14 in the plate and through the end wall 7 of the case. A nut 22 is threaded on the inner end of the bolt-shank and serves to securely bind the 80 plate against the end wall, the shoulder 20, however, preventing said bolt from clamping the head 17 of the bail-arm 10 and permitting the necessary pivotal action of the handle member. The outer end of the head 17 terminates in a shoulder 23, that co-operates 85 with the inner side of the rib, as hereinafter explained, and the arm 10, directly adjacent to said shoulder, extends across the outer face of the rib and rides thereagainst. This 90 portion of the arm is movable into and out of the notch 16, there being sufficient resiliency to insure the entrance of the arm into the notch.

The operation of the device may be briefly 95 described as follows: When not in use, the handle member can be elevated, and the arms 10 being located in the notches of the ribs will maintain said handle member in its elevated position. At the same time the operator may swing the handle member to either 100 side of the notch. It will be evident that with this structure when the sweeper is pushed away from the operator by the handle member the impulse will be transmitted 105 through the pivots 19, inasmuch as the handle member will bear against the same. When, however, the handle is drawn toward the operator, the draft will be brought against the ribs 15 and the pivots will be relieved 110 from the strain. As a consequence, the power will be applied at one side of the ver-

tical center of the sweeper-body. Therefore the danger of tilting said body is practically eliminated. It will be observed that this structure is very simple, that the parts may be easily manufactured and assembled, and that to apply the same to the sweeper-body it is only necessary to secure the plates to the flat surfaces of the end walls, there being no cutting or other fitting to be done.

10 A slightly-modified form of construction is illustrated in Fig. 5. The same plate is employed, and therefore the same reference-numerals have been applied thereto. The arm (designated 10^a) is provided with a head 11^a, having a shoulder 23^a, that cooperates with the rib in the usual manner. Instead of a pivot-bolt of the character above described the terminal of the arm or head is turned inwardly, as shown at 19^a, and engages in the opening 14 of the plate, said opening being of greater diameter than the body, so as to permit the necessary longitudinal movement of the arm and head with respect to the plate. The operation of the structure is the same as that already described, and a reiteration thereof is believed to be unnecessary. While this modified construction is more simple than the first-described embodiment and is therefore perhaps 30 cheaper to manufacture, it does not have the positive connection between the handle member and plate, for there is some chance of the pivot 19^a springing out of the opening.

From the foregoing it is thought that the construction, operation, and many advantages of the herein-described invention will be apparent to those skilled in the art without further description, and it will be understood that various changes in the size, shape, proportion, and minor details of construction may be resorted to without departing from the spirit or sacrificing any of the advantages of the invention.

Having thus fully described my invention, what I claim as new, and desire to secure by Letters Patent, is—

1. In a device of the character described, the combination with a sweeper-case, of a plate secured thereto, a handle member, a single pivotal connection between the lower end of the handle member and the central portion of the plate that permits a limited longitudinal movement of the handle member in both directions and prevents its detachment from the plate, an outstanding curved rib on the upper edge of the plate projecting beyond the outer face of said plate and dis-

posed substantially concentric to the pivot connection, and a shoulder carried by the handle member and bearing against the inner side of the rib upon the movement of said handle member in one direction.

2. In a device of the character described, the combination with a plate having an opening, and a curved marginal rib, of a handle-bail having an arm provided with an opening, a shouldered bolt passing through the opening of the arm and of less diameter than the same, said bolt passing through the opening in the plate and having its shoulder bearing against the same, and a draft-shoulder carried by the bail-arm and operating against the inner side of the marginal rib.

3. In a device of the character described, the combination with an outstanding curved rib having a notch, of a pivoted handle member having a shoulder bearing against the inner side of the rib and being movable into and out of the notch thereof.

4. In a device of the character described, the combination with a plate having a pivot-opening, and a rib concentric thereto, said rib having a notch, of a bail having a pivot engaged in the opening, said bail including an arm extending across and slidably associated with the rib, the arm being movable into and out of the notch thereof, and a shoulder carried by the arm and coacting with the inner side of the rib.

5. In a device of the character described, the combination with a sweeper-case, of a plate secured to the end thereof and having an opening, a marginal outstanding rib carried by the plate and having a curved portion disposed substantially concentric to the opening, said rib having a notch in an intermediate portion, a handle-bail having an arm provided with a head that operates over the plate, said arm being movable into and out of the notch of the marginal rib, and said head having a shoulder that operates against the inner side of the rib, and a pivot connecting the head and plate, said pivot engaging in the opening in the plate and permitting a slight longitudinal movement of the arm and head with respect to said plate.

In testimony that I claim the foregoing as my own I have hereto affixed my signature in the presence of two witnesses.

HIRAM W. RUTON.
